UNITED STATES PATENT OFFICE.

JOHN E. WRIGHT, OF NEW YORK, N. Y., AND J. HOLMES LONGSTREET, OF HOBOKEN, NEW JERSEY.

RELAY.

SPECIFICATION forming part of Letters Patent No. 243,824, dated July 5, 1881.

Application filed March 28, 1881. (Model.)

To all whom it may concern:

Be it known that we, JOHN E. WRIGHT, of the city and county of New York, in the State of New York, and J. HOLMES LONGSTREET, 5 of Hoboken, in the county of Hudson and State of New Jersey, have invented certain new and useful Improvements in Relays; and we do hereby declare that the following specification, taken in connection with the drawings furnished and forming a part of the same, is a clear, true, and complete description of our invention.

The prime object of our improvements is to obtain sensitive, accurate, and reliable relay 15 service with a minimum necessity for variable adjustment to meet the variable conditions incident to line service; and in attaining those ends we have made sundry special improvements in construction which have value in various connections, as will hereinafter be fully described.

Relays embodying certain features of our invention are operated by a local-battery current peculiar to the relay and by the line-current, the forces developed by these currents 25 acting through electro-magnets and serving to impart reciprocating motion to a vibrating element, as is essential in all relays.

Broadly considered the employment of local 30 and line currents for working relays is not new, and instances of prior relays operating upon this general principle will hereinafter be more fully considered.

Relays embodying certain of the important 35 features of our invention are novel in that on one side of the vibrating element there is a magnet wholly controlled by a line-helix, and on the opposite side a magnet having a double helix for separate local and line currents. In 40 their best form our relays embody a vibrating hollow slotted core within a helix, which is connected with the line-current helix before referred to. In such a relay the line-current simultaneously polarizes the free end of the 45 core oppositely to the polarity of the local-current magnet, weakens the force of the latter, and charges the opposite magnet with a polarity opposite to the polarity of the free end of the core, thus rendering our relay extremely 50 sensitive and reliable in operation.

The several features of our invention, after being fully described, will be specified in detail in the several claims hereunto annexed.

Referring to the accompanying drawings, of which there are three sheets, Figure 1, Sheet 55 1, represents, in side view, a relay in a desirable form and embodying all of the features of our invention. Fig. 2 represents the same in longitudinal central vertical section. Fig. 3 represents the same in plan or top view. Fig. 60 4, Sheet 2, is a detached view of an electro-magnetic bar which constitutes the vibrating element in the relay. Fig. 5 is a graphic illustration of the apparatus to aid in the explanation of our novel method of controlling 65 such apparatus. Fig. 6 is a modification illustrating the use of two movable cores with other elements. Fig. 7 is a modification illustrating the use of a single-line helix and a movable core with other elements. Fig. 8, 70 Sheet 3, is a modification illustrating the use of a single-line helix and a magnetic bar with other elements. Fig. 9 is a modification illustrating the use of two electro-magnets coupled to the same local battery and a vibrating core 75 with its helix. Fig. 10 is a modification illustrating the use of a vibrating polarized bar with an electro-magnet in the line-circuit and an electro-magnet controlled by a local battery modified by a helix in the line-circuit. Fig. 11 80 is a modification illustrating the use of two permanent magnets with a vibrating core and helix.

The apparatus shown in Figs. 1 to 4, inclusive, is well adapted for general relay service. 85 The bed-plate is composed of the usual material and channeled or scored on the under side for properly housing the various wire-connections, and has a requisite number of screw-posts, which will be hereinafter specially designated.

In this preferred embodiment of our invention we employ three electro-magnets, one of them having a vibrating core. The main or line magnet A is complex, and is, in substance, 95 two magnets co-operating substantially as one electro-magnet. The top bar, a, core b, base c, and helix d constitute one of said magnets, and the vibrating core e, pivoted to the base-bar c, and the helix f constitute another mag- 100

net. The two helices are in the line-circuit, and when the several parts thus far described are charged as an electro-magnet the upper end of the vibrating core is drawn to and 5 firmly held by the coincident end of the top bar, *a*, and when the line-current terminates the coincident portions of the top bar, and vibrating core are no longer magnetically controlled. The vibrating core is polarized by 10 both of the helices—*i. e.*, by helix *f* directly, and by helix *d* *via* base-bar *e*, to which the core is directly pivoted, and with either of said helices the movement of the vibrating core (if within a helix) or magnetic bar (if not within 15 a helix) may be effected; but we prefer both, as shown, for attaining the best results, without limiting ourselves thereto, except as hereinafter specified. This vibrating core or electro-magnetic bar has been specially designed 20 with reference to particularly favorable mechanical and electrical conditions. Mechanically it should be capable of movement with a minimum of friction, and it is therefore made light, is mounted truly vertically, is balanced, 25 and is delicately pivoted by two side screws, *e'*, having conical bearings and on a line with, but at right angles to, its axis. Electrically it should be capable of prompt electric or magnetic alternate charge and discharge, and it is 30 therefore constructed by us of soft iron, tubular in form and longitudinally slotted. These several conditions being thus provided for, it will be seen that the prompt and effective control and release of the movements of the magnetic core or bar are fully assured. 35

We are aware that stationary cores of electro-magnets have heretofore been hollow and slotted, and that hollow slotted longitudinally curved cores have been heretofore employed 40 in apparatus for feeding carbon points in electric lamps, in connection with segmental helices, within and by which said cores are longitudinally drawn, as by a weight or spring; and also that vibrating solid cores or bars have 45 heretofore been employed within helices in relays and in pole-changers worked by co-operative local and line currents.

We are further aware that heretofore a hollow slotted armature has been employed in 50 connection with magnets which alternately attract opposite ends of said armature, the latter having been so pivoted centrally on a standard between the magnets as to admit of the tilting movement of the armature. So far 55 as our knowledge extends, however, we are the first to combine a pivoted vibrating hollow slotted core within a helix, and in a relay worked by co-operative local and line currents, or in a relay worked by line-currents and per- 60 manent magnets, as hereinafter indicated, and we believe said hollow slotted core and its surrounding helix to constitute a novel feature in such relays, which is vital to their successful operation, because of the peculiar ne- 65 cessity therein for such a prompt charge and discharge of magnetism as will enable the core, even with a weak line-current, to be promptly

disengaged from the normal custody of electro or permanent magnets, as the case may be.

While we prefer the pivoted hollow slotted 70 core and helix, other forms of vibrating bar may be employed in connection with certain other features of our invention, as hereinafter indicated.

In sounders as heretofore contructed, in some 75 cases, a permanent magnet has been employed in opposition to the line or main current; but our experience develops the fact that for relay service, or any other service involving a wide 80 variation in the conditions incident to operation, the permanent magnet is generally ob- jectionable for several reasons, some of which we will cite, as follows: A permanent magnet is speedily weakened by the variation of op- 85 posing battery-currents to which it is or may be necessarily subjected, although we herein- after describe a novel combination embracing 90 portions of our invention and permanent mag- nets which are not adversely affected by bat- tery-currents. Again, its maximum capacity 95 is fixed and predetermined, and in any emer- gency, when greater power is required, it can- not be augmented unless the permanent mag- net be also an electro-magnet, as hereinafter indicated.

With a battery-current, the coupling or uncoupling of cells or the setting of switches in 95 battery-circuits enables a prompt and effective adjustment from the minimum or weakest force, easily obtained by a permanent magnet, to a 100 practically unlimited force, not practicably at-tainable with a permanent magnet.

We will now designate the course of the 105 electric currents and means through which they operate for effecting and controlling the opposite movements of the upper end of the 110 vibrating core in the relay already described.

The local-battery force is applied to the elec- 115 tro-magnet *B* with a constant polarity through the helix *g*, surrounding the core *h*, the front 120 end or face of which is coincident to one side of the upper end of the vibrating magnetic bar or core *e*, the helix and core constituting an electro-magnet, which normally always attracts said vibrating core or bar.

The core *h* is rendered longitudinally adjust- 125 able within its helix by means of thumb-screw *h'*, for the purpose of variably locating its face with relation to the position of the upper end of the vibrating core, the latter being prefer- 130 ably so limited in its movement that no me- tallic contact occurs with the face of core *h*. By this adjustment the electro-magnet *B* may exercise much or little attractive force with reference to the vibrating core or bar *e*.

We are aware that it is not broadly new in 135 a relay to provide for the adjustment of elec- tro-magnets with relation to the moving or vibrating element; but we know of no prior sliding core longitudinally adjustable with re- 140 lation to a vibrating core or bar within a helix, as herein described.

It will be seen that with the pole of electro- 145 magnet *B* permanently north, and the upper end

of the vibrating magnetic core or bar *e* south, under one of its variable polarities, the normal position of the vibrating bar will be adjacent to the face of the core *h*, and that when 5 the helices *d* and *f* are charged by the line-current to polarize south the face of the top bar, *a*, the same current, operating through helix *f*, polarizes north the upper end of the vibrating core *e*, thus neutralizing the attraction between said core and the electro-magnet *B*, simultaneously accompanied by an attractive 10 influence for carrying the upper end of the vibrating core to its opposite limit of movement and placing it wholly under the custody of the line-current; and, further, that when the line-current ceases the vibrating core is released 15 and passes to the custody of the electro-magnet *B*, the face of bar *a* meantime changing to a light north, by induction *via* magnet *B*, and 20 the upper end of the movable core changing to a light south, and in the best possible condition to be attracted by the magnet *B*. To render this variation of forces which we apply 25 for effecting the vibratory movements of the core still more sensitive, we introduce the neutralizing or opposing helix, *i*, which is interwound with or located outside of the helix *g* of magnet *B*, and is so arranged with reference 30 to the line-current and to said helix *g* that the line-current will reduce the electro-magnetic 35 force in the magnet *B*. The line-current, in operating upon this local current in electro-magnet *B*, not only reduces the power of said magnet, but it also reduces or weakens the 40 normal south of the movable core, which it derives through induction from the north of magnet *B*, and therefore the movable core is simultaneously released from said magnet and 45 oppositely attracted whenever the line-current is applied, all of the magnetic and electrical forces working in harmony to that end.

The binding-posts *k* and *k'* communicate respectively with line and ground, the current midway traversing helices *d*, *f*, and *i*. The 50 binding-posts *k²* and *k³* communicate with the relay-battery *g'*, Fig. 5, which controls the electro-magnet *B*.

The vibrating core *e* is surmounted by a suitable neck, *e²*, having a proper contact point for 55 engaging with the screw-stop of the sounder-circuit. The circuit including the sounder *l* and battery *l'* is made through the vibrating core, the conducting-wires terminating respectively at the base bar *c* adjacent to the foot of the vibrating core and at the front stop, *e³*, *via* the binding-posts *k⁴* and *k⁵*.

We are aware that in relays, as heretofore constructed, for operation by means of co-operating local and line currents an invariably- 60 polarized vibrating rod or bar has been encircled by a helix traversed by a local current, and the free end of said bar vibrated between the poles of an electro-magnet embodying separate helices traversed respectively by local and 65 line currents; and we are also aware that other relays operated by local and line currents have heretofore embodied a variably-polarized vi-

brating rod or bar, surrounded by a line-helix and vibrated between the poles of electro-magnets controlled wholly by the local current, 70 and the poles of electro-magnets controlled wholly by line-currents. We are also aware that in English Patent 1,452 of A. D. 1856 it is suggested that a local current and a line-current be employed in the operation of a relay in such a manner that the line-current and the local current alternately traverse the same 75 helices.

We are also aware that local currents have heretofore been employed, in connection with 80 line-currents, for operating relays and pole-changers by the reversal of one or both of said currents; but, as before herein indicated, we know of no prior relay which embodies a pivoted vibrating core or bar of any kind the free 85 end of which vibrates from one pole of a magnet or magnets having a local and a line helix to another pole of a magnet controlled wholly by a line-helix. We deem it of great importance, as before stated, that said vibrating core 90 or bar be variably polarized, as described, by the line-current, and also that said core or bar be hollow and slotted and located within a helix.

We are aware that apparatus embodying 95 more or less of our several features of invention may be devised in almost endless variety of construction and arrangement, and we will next describe a few of many such organizations developed by us.

The variably-polarized hollow and slotted core, because of its lightness and capacity for rapid charge and discharge, is well adapted for use in duplicate for vibrating as one core in the same relay, especially with weak line-currents.

In Fig. 6 we have provided two hollow slotted vibrating cores, *e'*, mounted vertically but pendent on horizontal pivots *e'*, and having a neck for vibrating above the pivot between front and back stops.

The line-helix *f* at the left hand is as before described, but its fellow at the right hand is a complex helix, *f'*, in two divisions, one of which is in circuit with the line-helix *f*, the two being so wound as to polarize by the line-current the left-hand core south and the right-hand core north. The second division of helix *f'* is in circuit with the local relay-battery as before described, and also with the helix *g* of the electro-magnet *B'*, having a T-shaped core, *h*, which is polarized constant north. Normally the right-hand core is in the custody of the arm of core *h* adjacent thereto, because the local relay-battery current polarizes the lower end of the right-hand core south, the left-hand core being then north. When the line-current is applied the left-hand core is polarized strong south, the right-hand core is reversed to north, and the core *h* being always 125 north, the cores move to the right hand, bringing the left-hand core into custody of the magnet *B'*, from which it is released, to resume its 130 normal position when the line-current ceases,

these movements of the cores making and breaking the currents in the sounder-circuit, as before described. These same parts may be modified as follows: Instead of having the two cores 5 vibratory, as shown, they may be fixed or stationary, and the arm which now vibrates between the stops be located upon the outer end of core *h* of magnet *B'*, pivoted so that the latter may vibrate to and from each of the cores, 10 and in this latter case the helix *g* may be stationary, so that the core *h* may vibrate therein, like the present cores.

We are aware that duplicate cores have heretofore been employed in pole-changers in connection with local and line currents; but we 15 know of no prior relay in which one of said vibrating cores was surrounded by a double helix for separate line and local currents, as shown in Fig. 6 at *f'*, and we deem that a desirable feature in connection with the vibrating hollow slotted cores when thus employed in duplicate.

In Fig. 7 we show a simple embodiment of the magnet *B'*, the vibrating polarized core *e*, 20 and its helix *f*; but in this form the magnet *B'* may or may not have the extra counterbalancing-helix connected with the line, as before described, and if not the local or relay current should be so adjusted that at its best its power 25 over the vibrating core may be readily overcome by the line-current, which is aided by the fact that the upper end of the core is by the line-current oppositely polarized, and therefore freely released by the magnet *B'*.

Referring to the relay, Fig. 7, it will be understood that the feature of our invention therein involved consists of the combination of the 30 vibrating hollow slotted core and the helix surrounding the same. The combination therein embodied of a local-current electro-magnet, a line-helix, and a variably-polarized vibrating bar is not broadly new; but we know of no prior relay in which the core-helix is solely relied upon to work against the local-current 35 magnet, it having heretofore been augmented by additional magnets co-operating with said core-helix, and we believe that said additional magnets cannot be practically dispensed with in such an organization, except by the use of 40 the hollow slotted core, as in our novel combination.

In Fig. 8 the magnet *B'* is or may be provided with the line-helix as well as the local-battery helix, as first described; but the polarized vibrating bar *e'* is not surrounded by a helix, reliance being had upon the helix *d*, its core, top bar, *a*, and base *c* for affording the requisite magnetic action due to the line-current. In this relay, Fig. 8, we have embodied 55 certain features of our invention, in that it contains an electro-magnet having a line and a local helix, a magnet having a line-helix and a variably-polarized core or bar, which vibrates between the poles of said magnets.

In Fig. 9 the magnet *B'* has only the local-battery helix, but said magnet is located opposite magnet *B²*, which has also a helix in the

local-battery circuit. The vibrating core *e* and its helix *f* are as before described, and the line-current also traverses an opposing helix in 70 magnet *B²*. With the magnet *B'* set at, say, one-half the power of magnet *B²*, the coincident poles being both constant north and the upper end of core *e* being slightly south by induction, it is obvious that it will normally 75 be held by magnet *B²*; but when the force of the latter is wholly neutralized or slightly reversed by the line-current, and by the same current the upper end of the core is polarized strong south, it moves promptly over to the 80 custody of magnet *B'*, from which it is as promptly released when said current ceases.

In Fig. 10 the electro-magnet *B³* has a local-battery helix, and also a helix in the line-circuit, as before described, the upper end of its 85 core being polarized constant north by the local-battery helix, and reduced to *nil* by the line-current helix. The upper end of the core of electro-magnet *B⁴* is polarized south by the line-current, as before described. The vibrating polarized bar *e'* differs from all others before described, in that it has a permanent bar-magnet, *e⁷*, which plays between the poles of the electro-magnets *B³* and *B⁴*. The left-hand end of said bar-magnet is polarized south and 90 the right-hand end north, so that in its normal position it is in the custody of magnet *B³*; but when the power of said magnet is wholly reduced by its line-current helix, and the magnet *B⁴* under the influence of the 95 line-current, it passes to the custody of said magnet *B⁴*, from which it is released and returned to magnet *B³*, when the line-current ceases. In this relay, Fig. 10, we have also embodied important features of our invention, 100 in that it contains an electro-magnet having a line helix and a local helix, a magnet wholly controlled by a line-helix, and a pivoted bar which vibrates between the poles of said magnets.

While we prefer to avoid the use of permanent magnets in any form, we have shown their embodiment with certain of our novel features to illustrate some of the numerous combinations in which portions of our improvements may be organized.

In Fig. 11 we show two permanent magnets (one of which is also an electro-magnet having a line-helix) and our vibratory core and helix. For use with one or more permanent magnets, substantially as in this relay, we believe the combination of the variably-polarized pivoted vibrating hollow slotted core and its inclosing-helix has special value, because of its lightness and its capacity for 115 prompt magnetic charge and discharge; and we further believe that a relay embodying one or more permanent magnets cannot be successfully operated without the hollow slotted pivoted core and its helix unless the permanent magnet be mounted upon the vibrating bar, as in Fig. 10, with which fair results may be obtained. The permanent magnet *C* takes the place of the electro-magnet *B*, first de-

scribed, and its condition is not varied by the line-current. The magnet C' is also permanent, but its force is at intervals augmented by the line-current helix thereon. The lower 5 pole of magnet C is north and the lower pole of magnet C' south, but much weaker than magnet C. Normally the vibrating core e will be in custody of magnet C, but the line-helix of the vibrating core in this case is so wound 10 that it charges said core north, causing it to be readily released from magnet C and attracted by magnet C', which meantime by its line-helix has had its power augmented; but after the line-current ceases the magnet C resumes the custody of the core, because of its 15 greater power. In all apparatus embodying such permanent magnets the adjustment of the core must of necessity be very close to the poles of the magnets and the extent of vibration limited, and, as in all the apparatus described, metallic contact of the core and magnets should be avoided.

It will be observed that wherever we employ permanent magnets we in no case so apply 20 the line-currents as to produce a weakening of said magnets. In the bar-magnet e⁶ of Fig. 10 the varying conditions of the two magnets co-operating therewith are always in harmony with the bar; and in Fig. 11 the magnet C' is 25 never reduced from its normal or original magnetic condition, but is, on the contrary, augmented by the line-current tending to gradually increase its permanent force, rather than to decrease it.

30 It will also be observed that with each of the several forms of apparatus shown a line-current of unchanged polarity is employed.

In the construction of our apparatus we 35 purpose the employment of the best known

materials, and to avail ourselves of the best 40 features of construction well known to be applicable and desirable in electrical apparatus, and we have not deemed it necessary to enter into all the specific details in those connections.

Having thus described our invention, we 45 claim as new—

1. In a relay, the combination, substantially as hereinbefore described, of an electro-magnet having a local and a line-helix, an electro- 50 magnet wholly controlled by a line-helix, and a pivoted vibrating core or bar which at its free end vibrates between the poles of said magnets.

2. In a relay, the combination of a pivoted 55 hollow longitudinally-slotted core and a helix surrounding said core, substantially as described.

3. In a relay, the combination of the variably-polarized vibrating core, a line-circuit helix surrounding said core, an electro-magnet having a line-helix co-operating with the core-helix for moving the free end of the core in one direction, and an electro-magnet for moving said core in the opposite direction, provided with separate helices for line and local 60 currents, substantially as described.

4. In a relay, the combination, with one or two helices, of a vibrating core or bar variably polarized and an electro-magnet of constant 65 polarity provided with separate helices for local and line circuits, substantially as described.

JOHN E. WRIGHT.
